APPARATUS FOR MAKING NECKTIES

Nathan Gold, Portland, Oreg.

Application September 14, 1936, Serial No. 100,644

4 Claims. (Cl. 223—110)

This invention relates to necktie manufacture and more particularly to apparatus for and a method of manufacturing neckties by hand-sewing or hand-stitching.

5 It is a general object of the present invention to provide new and novel means for quickly, conveniently, and accurately positioning the various elements of a necktie structure in proper relation and alignment with respect to each other in preparation for the stitching operation.

Another object of the invention is the provision of apparatus of this character in table form having movable platforms associated therewith so the necktie may be dealt with from end to 15 end while the operator or a number of them may remain in one position.

These and other objects will appear as my invention is more fully hereinafter described in the following specification, illustrated in the accompanying drawings and finally pointed out in the appended claims.

In the drawings:

Figure 1 is a top plan view of my new and improved apparatus.

25 Figure 2 is a side elevation of Figure 1.

Figure 3 is an enlarged sectional view taken on the line 3—3 of Figure 1.

Figure 4 is an enlarged side elevation of a clamping mechanism, with parts broken away 30 and parts in section for convenience of illustration.

Figure 5 is an enlarged fragmentary top plan view of one of the movable tables showing in particular an elongated cavity or receptacle with- 35 in the table for receiving the structural elements of the necktie, and means running lengthwise of the cavity to serve as a guide for, first, the pinning operation and then the stitching operation.

Figure 6 is a sectional view taken on the line 40 6—6 of Figure 5.

Figure 7 is a sectional detail view of a modified form of pinning guide.

Figure 8 is an enlarged perspective sectional view through the table and cavity, and showing the tie elements in process of assembly.

Referring now more particularly to the drawings:

Reference numeral 1 indicates a stationary tray 50 or platform secured to transverse members 2 and 3 which are supported by legs 4 and 5. On each side of the tray 1, I provide movable work tables 6 and 7 which are mounted upon rollers 8 for movement lengthwise of the apparatus. The 55 rollers 8 are rotatably mounted by any suitable

means to the legs or transverse members of the supporting structure.

Both tables 6 and 7 are identical with each other, and a description of one will suffice for both. Moreover, it is to be understood that any 5 number of work tables may be arranged or provided so that any number of operators may be stationed along a production line or on both sides thereof.

In each work table I form an elongated cavity 10 or receptacle 9 for receiving the various structural elements of a necktie about to be assembled and sewed together. The cavity may be entirely routed out of the table, or its outside wall may be formed by a strip of any suitable material as 15 indicated at 10.

Running centrally of the cavity and extending from end to end thereof, is a channelway 11 which may be formed by two separate vertically disposed parallel walls 12 and 13, or it may be 20 formed of a single strip of material shaped as shown in Figure 7.

Along the rear edge of each table I provide a support 14 of bifurcated formation upon which is slidably mounted the clamping mechanism illustrated in Figure 4. The support for the clamping mechanism comprises a blade 15 slidably embraced by the bifurcated support 14. Superimposed upon the blade is a stud 16 to which is swingably mounted an arm 17 by means of a 25 collar 18.

Extending outwardly from the arm 17, and pivotally connected thereto, as at 19, is a supplemental arm 20. This arm is normally held in a raised position by a spring 21 interposed between the underside of the arm 20 and a projection 22 formed on the arm 17. 35

The outermost end of the supplemental arm is provided with a cap 23 backed by a spring 24 and a friction disc 25. A cam 26 is provided on the 40 arm 17 and is adapted to raise and lower the supplemental arm 20.

To the legs of the supporting structure I swingably attach suitable trays 27 and racks 28 for convenience of the operators in dealing with materials to be used.

Operation

In forming a necktie, in accordance with my invention, I first place the necktie lining 29 with- 50 in the cavity 9 whose outline is precisely the same as that of the lining. Along the top of the lining I place a reinforcing strip 30 which ordinarily is of less width than the lining. In assembling a necktie it is important that the reinforcing strip 55

be arranged symmetrically on both sides of the stitching line, and that the stitching line extends along the exact centerline of both the lining and the reinforcing strip. By ordinary methods this 5 precise arrangement is slow and tedious to accomplish and due to the extra time and work involved renders the cost of producing handmade ties rather expensive. But in my new and improved machine I overcome these disadvantages 10 by providing a means, in the form of the channelway 11, which, as previously stated, runs full length of the cavity along its centerline and underlies the centerlines of the lining and reinforcing strip when they are placed within the cavity. With the lining and reinforcing strip thus 15 arranged within the cavity, the necktie casing material 31 is folded over on itself to bring its two outside edges into alignment with each other, as illustrated in Figure 8. The casing thus folded 20 is then placed upon the reinforcing strip and is then pinned to it and to the lining along the line within, and defined by, the two ridges of the channelway. In first pinning these various elements 25 together the operator determines the exact centerline of the lining and reinforcing strip by the sense of touch as one of her fingers advances along the channelway as the pinning operation advances.

In some instances, due to differences in texture 30 of the tie material being dealt with, it is desirable to provide wider seams in some tie material than in others. By width of seam I mean the distance between the aligned edges of the necktie casing material, as aforesaid, and the line of 35 stitching arranged inwardly therefrom. The wider the seam, of course, the less chance there is for raveling, and by means of the channelway 11 the width of the seam may be easily determined as the necktie casing is placed over and pinned to 40 the lining and reinforcing strip. However, regardless of the width of the seam in the tie-material the stitching of the lining and reinforcing strip remain the same, namely, along the centerlines of both elements.

Following this aligning and pinning operation, 45 the assembled elements are then removed from the cavity and may be arranged lengthwise of the table or transversely thereof, as most convenient for the operator, for the stitching operation.

For securing the tie elements to the table for the stitching operation, the clamping mechanism, heretofore described, is swung outwardly from its support and by means of the cam mechanism 26 is forced downwardly against the tie, and as the 5 stitching operation progresses, the clamp may be removed or loosened to make way for the stitching.

I claim:

1. Apparatus for manufacturing neckties, comprising a table, a receptacle within the table for receiving the structural elements of a necktie, and means within the receptacle for guiding the pinning of the tie elements in preparation for the stitching operation. 10

2. Apparatus for manufacturing neckties, comprising a movable table, a receptacle within the table for receiving the structural elements of a necktie, means within the receptacle for guiding the pinning of the tie elements, and adjustable 20 clamping means for securing the tie elements within the receptacle. 15

3. Apparatus for manufacturing neckties, comprising a table, an elongated receptacle within the table for receiving the unattached structural 25 elements of a necktie, means within the receptacle and running lengthwise along the centerline thereof for guiding the pinning together of the tie elements, said means comprising a channelway elevated from the bottom wall of the receptacle whereby an operator may by the sense of 30 touch determine the centerline of the receptacle and the tie elements therein during progress of the pinning and stitching operations, and adjustable clamping means for maintaining the tie elements within the receptacle. 35

4. Apparatus for manufacturing neckties, comprising a support, a plurality of tables movably mounted upon the support, each of said tables having an elongated receptacle formed therein to receive the structural elements of a necktie, means within the receptacle for guiding the pinning and stitching of the tie elements along the centerlines of said tie elements, and clamping means for securing the tie elements within the 40 receptacle. 45

NATHAN GOLD.
